UNITED STATES PATENT OFFICE.

CYRUS M. BAKER, OF BINGHAM, MAINE.

LUMBER-DRIVER'S CALK.

SPECIFICATION forming part of Letters Patent No. 230,686, dated August 3, 1880.

Application filed June 17, 1880. (No model.)

To all whom it may concern:

Be it known that I, CYRUS M. BAKER, of Bingham, in the county of Somerset, in the State of Maine, have invented a new and useful Improvement on Lumber-Driver's Calk; and I do hereby declare the following specification and its drawings to be a full, clear, and exact description of my invention.

This invention, resembling a pointed spike, is inserted at different places into the soles of a lumberman's boot in order to help him walk safely upon ice or ice-covered logs or surfaces, or wherever a sure footing is necessary.

The invention consists in a calk having a steel center and point, but an exterior body of iron.

It further consists in providing the calk with a shoulder to keep it from dropping out and a flange to prevent it from being driven too far into the boot.

In the drawings, Figure 1 represents the calk as set in the sole of a boot; Fig. 2, a view in perspective, and Fig. 3 a view in section.

The center of the calk *a* and both ends of it are constructed of steel. It is made of steel for its entire length. Except at the extreme ends of the calk, it is covered with iron *m*. Above the point *n* is a flange, *o*, to prevent it from being driven too far into the leather.

Between the flange and the inner or upper end 30 of the calk is a shoulder, *s*, to prevent the calk from dropping out of the boot if the leather shrinks about the calk.

When this calk is formed under the hammer or by other means of compression the iron 35 and steel are drawn uniformly to a point together. The steel portion can thus be made very hard without danger of breaking it, as it is surrounded and supported by the iron.

The calk can be made harder than if it were 40 made entirely of steel. It is stronger, and it will wear sharper and last longer from having an iron exterior.

What I claim as new, and desire to secure by Letters Patent, is—

1. A calk composed of a steel body and point and an exterior surface of iron.
2. A calk having a steel body and point, a flange, *o*, and shoulder *s*, substantially as described.

In witness whereof I hereinunto set my hand, in presence of two attesting witnesses, this 29th day of May, 1880.

CYRUS M. BAKER.
